UNITED STATES PATENT OFFICE.

CHARLES O. HEMBREE, OF ASHER, OKLAHOMA.

PLOW.

1,155,418.

Specification of Letters Patent.

Patented Oct. 5, 1915.

Application filed June 28, 1915. Serial No. 36,477.

To all whom it may concern:

Be it known that I, CHARLES O. HEMBREE, a citizen of the United States, residing at Asher, in the county of Pottawatomie and State of Oklahoma, have invented certain new and useful Improvements in Plows, of which the following is a specification, reference being had to the accompanying drawings.

10 My present invention pertains to new and useful improvements in plows and has for its principal object the construction of a plow in which the standard is pivotally attached to the beam by means of a novel 15 adjusting mechanism which may be readily manipulated to vary the angular relation of the standard to the beam.

A further object of the invention is to provide in connection with the angularly 20 adjustable standard, an adjustable shoe which is pivotally attached to the standard adjacent the lower terminal thereof and is disposed for engagement with the ground, being adjustable in such manner that the 25 depth to which the plow share or shovel may engage in the ground will be controlled by the position of the shoe.

The above, and other incidental objects of a similar nature, which will be hereinafter 30 more specifically treated are accomplished by such means as are illustrated in the accompanying drawings, described in the following specification, and then more particularly pointed out in the claims which are 35 appended hereto and form part of this application.

With reference to the drawings, wherein 40 there has been illustrated the preferred embodiment of this invention, as it is reduced to practice, and throughout the several views of which similar reference numerals designate corresponding parts, Figure 1 is a side elevation, partly in section; Fig. 2 is a section on the line 2—2, of Fig. 1; and Fig. 3 45 is a section on the line 3—3, of Fig. 1.

In the embodiment of the invention shown in the accompanying drawings and best illustrated as an operative entirety in Fig. 1 thereof, the plow consists broadly in a beam 10; a standard 11, a ground engaging shoe 12, and means for adjustably connecting the standard to the beam and the shoe to the standard.

The beam 10 is of conventional design for 50 the most part, and is preferably formed

from wood, although metal may be employed, if so desired. In the lower face of the beam is formed a longitudinal groove, indicated at 13. The lower face or edge of the beam is also cut-away adjacent its rear end, as indicated at 14, so that the wear plate 15 may be secured to the bottom face to extend contiguous therewith. The wear plate is secured to the beam by bolts 16 and 17, which members pass vertically through the beam and serve also to secure the bracket plate 18 in place upon the upper face of the beam. In the wear plate is formed, as shown best in Fig. 1, a longitudinal slot 19 which registers with the groove 13. In the channel defined by the groove 13 and the slot 19, is disposed for sliding movement the flattened terminal 20 of the draft rod, indicated at 21. This flattened terminal 20 is apertured as at 22 to receive a bolt or equivalent element 23, by means of which the draft rod is pivotally connected to the standard in a manner which will be obvious upon reference to Fig. 3. The forward end of the draft rod is directed vertically, as at 24, and then rearwardly and horizontally as at 25, forming thereby a clevis, which embraces the forward end of the plow beam. The member 24 is spaced from the forward end of the beam, as in Fig. 1, and is provided with holes 26, through which the link for securing the double-trees or other draft animals may be applied. The horizontal member 25 is provided with a bolt receiving aperture 27, which aligns with an opening 28 formed in the draft rod. Through these two openings is passed a draw bolt 29. This member 29 passes through a longitudinal slot 30 formed in the beam. It is necessary that the draw bolt be disposed in the slot 30 so that it may be longitudinally movable with respect to the plow beam for, as will be hereinafter explained, the draw rod is adjusted longitudinally with respect to the beam when the standard is to be angularly adjusted with respect thereto.

The standard heretofore designated as an entirety by the numeral 11, is preferably formed from two metal bars or plates 31 and 32, between the lower ends of which is mounted a spacer block 33. Passing through the members 31 and 32, at their approximate centers, is the transverse pivot bolt 34, which member passes through the lower terminal of the supporting bar, indicated at 35. This

member 35 is directed forwardly and downwardly with respect to the beam, having its rear terminal secured to the lower face thereof and against the wear plate 14, by means of the bolt 16. The upper terminal portions of the two bars 31 and 32 of the standard are laterally offset, as indicated at 37 and then extended upwardly in parallel spaced relation to each other, as at 38. The pivot bolt heretofore designated by the numeral 23 passes through the members 31 and 32 immediately above the offset 37. The upper terminals of the portions 37 extend to a point somewhat above the bracket plate 18 so that they may be pivotally attached by means of a bolt 39 to an L-shaped slide plate 40. This member 40 is, as shown best in Fig. 1, disposed for sliding movement upon the bracket plate 18 and is provided in its vertical portion 41 with an opening or aperture, which receives the stem 42 of the adjusting screw 43. The adjusting screw 43 is threaded through the vertical arm 44 of the bracket plate 18 and is provided at its rear end with a squared stub 45, upon which a crank or handle 46 is secured by means of a nut or equivalent fastening device.

From the description thus far given, it will now be apparent that the adjusting screw 43 may be operated to either move the slide plate 40 forwardly on the bracket plate 18 or to move it rearwardly thereon. Apparently the adjustment of the slide plate will accomplish the corresponding adjustment of the standard 11, since this member is mounted for pivotal adjustment about the bolt, as an axis. It will also be apparent that simultaneously with the adjustment of the standard, there will occur a longitudinal adjustment of the draw rod 21.

It now becomes apparent that when it is desired to adjust the standard to cause the shovel or share, which it carries, to bite a greater or less depth into the ground, such adjustment may be readily and easily accomplished by manipulation of the screw rod 43.

In order that there may be a further means for controlling the depth to which the plow share may bite into the ground, I have provided, as heretofore explained, the shoe member 12. This shoe is preferably formed from a single bar of metal which is shaped to include a relatively long body bar α , and an L-shaped connecting arm 47. The horizontal portion 48 of the member 47 is disposed between the bars 31 and 32, adjacent to the lower terminals thereof and pivotally secured in position by means of a bolt or equivalent element, indicated at 49. In the body bar 46, is formed a slot 50, in which is secured, by a bolt or equivalent element 51, the lower terminal of a vertically disposed bar, indicated at 52. The upper terminal of this member 52, is provided with a right-

angularly extending lug 53, having an opening indicated at 54. In this opening 54, is rotatably secured the lower end of an adjusting screw 55. A horizontally disposed bracket bar, indicated at 56 is seated in the rear end of the beam 10 and is provided with a threaded opening through which the adjusting screw passes, in the manner best disclosed in Fig. 2. The upper terminal of the adjusting screw is provided with an integrally formed handle, indicated at 57, which is operable in an apparent manner for manipulating the adjusting screw.

The above description will now make it apparent that the adjusting screw 55 may be readily manipulated by the user of the plow to dispose the body bar 46 of the foot 12 at any desired angle with respect to the standard. As disclosed in dotted lines in Fig. 1 the adjustment of this body bar with respect to the standard, provides for the controlling of the depth to which the plow share will dig into the ground.

I now desire to particularly point out that while I have provided in a plow, the angularly adjustable standard, and a shoe member, which is angularly adjustable with respect to the standard, the structural features employed in accomplishing these two ends are relatively simple and may, therefore, be easily operated and will not be likely to become broken or damaged during the use of the plow.

While I have shown and described the preferred embodiment of my invention it will be obvious that various changes in the details of construction and in the proportions may be resorted to for carrying my invention into practice without sacrificing any of the novel features or departing from the scope of the appended claims.

What is claimed, is:—

1. A plow including a beam, a standard including a pair of parallel spaced plates having their upper terminals disposed on opposite sides of the beam, a supporting bar having one end fixed to the under face of the beam at the inner end thereof and its other end inclined downwardly and disposed between the plates at their approximate centers, a bolt extending through the plates and the lower end of the supporting bar for pivotally mounting the standard, a draft rod carried by the beam and having one end connected to the standard, a slide plate movable over the upper face of the beam and pivotally connected to the upper terminals of the standard plates, one end of said plate being angularly disposed and provided with an opening, a bracket plate secured to the beam and arranged beneath the slide plate, and a screw rod movable in the bracket plate and having its inner end connected with the angularly disposed end of the slide plate for adjusting said slide plate.

plate longitudinally upon the beam, whereby the angular relation of the standard to the beam may be varied.

2. A plow including a beam, a standard supported by the beam for pivotal movement, a ground engaging member including a relatively long body bar, an L-shaped connecting arm formed at one end thereof, the horizontal portion of said arm being pivotally connected to the standard adjacent the lower terminal thereof, a bar having pivotal connection with the body of the ground engaging member, an angular lug at the upper end of said bar, having an opening therethrough, a supporting bracket carried by

the beam and arranged in alignment with the angular lug, a vertically disposed screw rod movably mounted within said bracket and having its lower end attached to the angular lug of the bar, and a handle formed at the upper end of the screw rod for operating the same to adjust the ground engaging member with respect to the standard.

In testimony whereof I hereunto affix my signature in the presence of two witnesses. 25

CHARLES O. HEMBREE.
